UNITED STATES PATENT OFFICE.

BENJAMIN F. FITCH, OF GREENWICH, CONNECTICUT.

GANTRY CRANE.

Original application filed July 14, 1920, Serial No. 396,061, now Patent No. 1,437,965, dated December 5, 1922. Divided and this application filed April 18, 1922. Serial No. 555,462.

To all whom it may concern:

Be it known that I, BENJAMIN F. FITCH, a citizen of the United States, residing at Greenwich, in the county of Fairfield and 5 State of Connecticut, have invented a certain new and useful Improvement in a Gantry Crane, of which the following is a full, clear, and exact description, reference being had to the accompanying drawings.

10 This invention relates to hoisting and transporting mechanism primarily adapted for raising and moving the bodies of automobile trucks, and for use in conjunction with the handling of freight at terminal 15 stations. My invention is well adapted for handling loaded truck bodies in a system for handling and transporting freight, as set forth in my copending application, Serial No. 396,061, filed July 14, 1920, now 20 Patent 1,437,965, issued December 5, 1922, and of which this application forms a divisional part.

I have illustrated my invention in connection with a raised platform between a rail-way track and truck runway wherein a 25 gantry crane straddles the platform and is arranged to travel longitudinally thereof. This crane has a supplemental frame on the main frame adapted to travel transversely of the freight platform track and runway. Thus I may accomplish lifting and carrying a container from a truck positioned on one side of the platform to a flat railroad car positioned on the other side, or vice 30 versa, or overhead to any place on the platform.

The principal feature of my invention is the arrangement of a gantry crane having a cantilever construction on the main frame, 40 together with other characteristics of construction which are illustrated in the drawings hereof and hereinafter described in detail. The essential features are summarized in the claims.

45 In the drawings, Fig. 1 is a side elevation of a crane embodying features of my invention and showing a platform intermediate a truck and railroad car; Fig. 2 is an end view of the gantry crane taken from the 50 street side of the platform; Fig. 3 is a plan view of the crane with a part thereof broken away to show details of construction; Fig. 4 is a view showing the elements of the driving mechanism of the crane; and Fig. 5 is a 55 plan view showing the supplemental frame

together with the means for moving it along the main frame.

Designating the parts shown in the drawings by the use of reference characters, 1 and 2 represent tracks preferably positioned on a 60 freight platform 3, and on which wheels 4 are adapted to travel. These wheels are supported in bearing blocks 5 at the foot of vertically disposed units, which form a support for the gantry crane; the tracks extend longitudinally of the platform, and are spaced apart sufficiently to permit several removable truck bodies 7 to be placed on the platform.

Referring now to Fig. 2, it will be seen 70 that each bearing block or carriage 5, carries a pair of wheels and that there are two pairs of such supporting wheels for each leg of the gantry. These legs, or vertically disposed supporting members, are preferably 75 right triangular in form, each having a vertically disposed leg 6, a base 17 and a hypotenuse 19. Each leg may be built up of four angle bars secured back to back but spaced 80 apart to provide clearance for suitable reinforcing members as embodied in lattice work. The base and hypotenuse of each unit may comprise a pair of angle bars positioned back to back, with sufficient clearance 85 between the members forming the hypotenuse to provide for lattice reinforcing work. This type of construction for each gantry leg prevents the crane from tipping when brought to a stop. Additional strengthening means may be provided between the supporting members which travel on the same 90 track, by connecting bars 18. These bars may be angle plates positioned back to back and connected to gusset plates at the base of the vertical members 6.

To move the crane longitudinally of the platform I provide a pinion 8 intermediate the wheels and spur gearing 8^a rigid with the wheels, adjacent one of the vertical supporting members of the gantry. This pinion 100 may be rotated through a set of bevel gears 9, which are driven through a shaft 10 by another set of bevel gears 11, positioned at the top of the vertical member 6. The upper set of bevel gears may be driven from 105 a worm and worm wheel connection 12, through a sprocket chain 13, by a motor 14. The motor may be mounted on the overhead structure, as illustrated in Fig. 3. The shaft 15, on which the worm wheel is secured, 110

preferably extends across the top of the crane and longitudinally thereof for operating a set of bevel gears 16 to drive another pair of wheels on the opposite track.

5 Referring now to Figs. 1 to 3, the main crane comprises a fabricated rectangular structure or frame, having longitudinal members 20 and 21, and end transverse members 22 and 23 respectively. The longitudinal members are preferably angle bars positioned back to back, while the transverse members may be channels which are attached to the ends of the longitudinal beams. The longitudinal members may be positioned at the top of the gantry legs and rigidly secured thereto. To prevent deflection of the longitudinal beams, I provide a truss having upper chords 24 and 25, purlins 26, and reinforcing members 27. The lower ends of the upper chords are preferably secured to the ends of the longitudinal members which form the lower chords by suitable gusset plates. The purlins extend transversely of the frame, and are rigidly secured to the upper chords, thus providing a suitable foundation for receiving a roof covering.

To provide overhead tracks for supporting the supplemental frame which travels transversely of the direction in which the main frame operates, I have shown a series of separated plates 30 and 31 which project inwardly from the base of the lower chords. These plates may be reinforced preferably by angles 32 and 33 which are positioned below the lower chords and rigidly secured thereto. Then, extending across the top of these plates I may provide I-beam supporting members 34 and 35, which carry tracks 36 and 37 respectively. Traveling on the overhead tracks 36 and 37, I provide a supplemental frame which moves longitudinally of the main frame, and therefore transversely of the freight platform.

45 The supplemental frame may comprise longitudinal members 40 and 41 with transverse end beams 42 and 43 respectively. Intermediate these end beams I may provide transverse beams 44 and 45 which provide bearing surfaces for wheels 46 and 47 traveling on the overhead tracks. To move the supplemental frame along the overhead trackway I provide pinions 48 and 49 intermediate gears on the wheels 46 and 47 and attached to the shaft 50. This shaft may be rotated by a motor 53. Suitable control mechanism (not shown) is provided for operating the motor, and a mechanical brake may be attached to the motor to retard supplemental motion of the frame when the frame is disconnected. Intermediate the ends of the longitudinal members 40 and 41, and between the transverse members 44 and 45, I may provide additional transverse beams 54 and 55. These last mentioned

beams may support a pair of reinforcing members 56 and 57, which in turn support the motor for operating the hoisting mechanism, as will be hereinafter described.

The hoisting mechanism may comprise a pair of winding drums 58 and 59 which are carried on a shaft 60 and are supported thereon adjacent the longitudinal beams 40 and 41. This shaft may be rotated through a gear 61 and pinion 62 by a motor 63. The hoisting elements are preferably embodied in pairs of cables 64 and 65, which extend outwardly from the drums 58 and 59 respectively, and pass over sheaves 66 and 67 which are respectively mounted on the transverse beams 54 and 55. The lower ends of the cables may be provided with any suitable load engaging means, but I prefer to employ loops 68 and 69 which are adapted to engage hooks 70 and 71 on the truck bodies. The cables are so arranged on the winding drums that a movement of the drums in one direction will wind in all of the cables, while a movement in the opposite direction will pay out all of the cables. Obviously, when the cables are wound in, the load depending therefrom will be raised, and when the cable is payed out the load will be lowered.

30 Suitable control cables 72 and 73 may depend from the supplemental frame whereby an operator may readily control the movement of the frame and hoisting elements, from a position on a freight platform.

35 It should be noted that a crane constructed according to my invention not only provides a substantial cantilever construction which enables the supplemental frame to move beyond either longitudinally extending track, but that each end is entirely open between the vertical legs, enabling a long vehicle body to be moved sidewise through such open ends, either substantially at the level of the truck or train floor or high enough to pass over a body on the platform.

40 Having thus described my invention, I claim:

1. The combination with a main frame, of four independent supporting members therefor, bridge members carried by the supporting members, a trackway carried by the bridge members, and extending beyond said supporting members, there being one track carried by each member, a supplemental frame traveling on said trackway, and transverse beams connecting said bridge members beyond the ends of the trackway.

45 2. The combination with a traveling main frame having a plurality of supporting members therefor, of two spaced bridge members carried by the supporting members, a track carried by each bridge member on the inner side thereof, a supplemental frame traveling on said tracks and trans-

verse beams connecting said bridge members beyond the ends of said tracks, whereby the space between the bridge members and connecting means is entirely free for load trans-

5 porting purposes.

3. The combination with a traveling frame having a plurality of supporting members therefor adjacent the four corners of a rectangle, an overhead trackway carried by the supporting members and overhanging the ends thereof, said supporting members providing an open runway from top to bottom, and triangular braces outside the runway for reinforcing the supporting members, said braces facing outwardly whereby an open vertical runway is provided between said supporting members.

4. The combination with a trackway, of four supporting members therefor, each member comprising a triangular support substantially in the vertical plane of the trackway and having an inner vertical leg, an inclined outer leg and a base adjacent the trackway, wheels mounted on each base, a longitudinal member on each side connecting the two bases, and an overhead transverse track connecting the tops of the four supports and supported thereabove.

5. The combination with a platform, of tracks carried thereby and extending longitudinally thereof, wheels on said tracks, a plurality of supporting members rising from the wheels, means extending longitudinally of the tracks and between the supporting members, transverse connecting means, comprising purlins, means connecting the bottoms of two supporting members over the same track, and positioned below the surface of the platform.

40 6. In a traveling frame, the combination

with a station platform, of tracks carried thereon and extending longitudinally thereof, wheels adapted to be moved on said tracks, the tops of said wheels being below the surface of the platform, four supporting members riding on the wheels, connecting means between the supporting members comprising trusses, a motor mounted on one of the trusses, a shaft connected with the motor and extending transversely of the platform, 45 and gearing connecting each end of the shaft with some of said wheels, whereby the frame may be moved.

7. The combination with a frame, of a plurality of supporting members therefor, 50 trusses connecting the supporting members near the top thereof, separated inwardly extending brackets rigidly secured to said trusses, track supporting means mounted on and connecting said brackets, and tracks rigidly secured to said track supporting means.

8. The combination with a main frame, carrying an overhead support, of separated brackets mounted on said support and projecting inwardly therefrom, a trackway supported on said brackets, and a supplemental frame adapted to move along said trackway.

9. The combination with a trackway, of a frame having a plurality of triangular supporting members therefor, each supporting member having two sets of wheels, one of said sets being carried by the toe of the supporting member, and the other of said sets being carried by the heel of the supporting member, said wheels being adapted to ride on the trackway.

In testimony whereof, I hereunto affix my signature.

BENJAMIN F. FITCH.
